UNITED STATES PATENT OFFICE.

ZENO M. SPEER, OF WAUWATOSA, WISCONSIN, ASSIGNOR TO SPEER CALENDAR BANK CO., OF MILWAUKEE, WISCONSIN, A CORPORATION OF WISCONSIN.

DESIGN FOR A COMBINED TOY MONEY BANK AND CALENDAR-PAD HOLDER.

Application filed June 14, 1928. Serial No. 27,127. Term of patent 3½ years.

To all whom it may concern:

Be it known that I, ZENO M. SPEER, a citizen of the United States, residing at Wauwatosa, in the county of Milwaukee and State of Wisconsin, have invented a new, original, and ornamental Design for a Combined Toy Money Bank and Calendar-Pad Holder, of which the following is a specification, reference being had to the accompanying drawings, forming a part thereof.

The figure is a perspective view of a combined toy money bank and calendar pad holder showing my new design.

I claim:

The ornamental design for a combined toy money bank and calendar pad holder, substantially as shown.

In witness whereof, I hereunto subscribe my name this 16 day of May, 1928.

ZENO M. SPEER.
